UNITED STATES PATENT OFFICE.

JONATHAN C. MELOON, OF PROVIDENCE, RHODE ISLAND.

AUTOMATIC ATTACHMENT FOR FIRE-EXTINGUISHER SYSTEMS.

Application filed March 16, 1921. Serial No. 452,816.

To all whom it may concern:

Be it known that I, JONATHAN C. MELOON, a citizen of the United States, residing at Providence, in the county of Providence and State of Rhode Island, have invented certain new and useful Improvements in Automatic Attachments for Fire-Extinguisher Systems, of which the following is a specification.

This invention relates to improvements in automatic alarm attachments for wet-pipe fire extinguishing systems. Alarm apparatus at present found in the market is liable to work intermittently. It is an object of the invention to provide apparatus that will continue the operation of the alarm or other apparatus without interruption until stopped by human interference. It is a further object of the invention to construct the apparatus so that it will be capable of putting into action whatever number and variety of apparatus may be desired, with sufficient power to operate each, including for example, a water motor, or a pump starting apparatus. I have already, in my United States Patent No. 1,401,175, disclosed and claimed broadly apparatus for accomplishing this, in which the specific means of attaining the object is a swinging arm, operated by the parts which move to close the drip chamber as already well known, which arm opens a valve to admit water and pressure from the main supply sufficient to maintain the status and to operate the desired apparatus. The present is a species of this generic form, in which the objects are attained by setting a T-coupling of special design in the line of pipe which is provided to operate the alarm or other apparatus, (usually in the drip pipe from the intermediate chamber of an alarm valve in the main riser) provided with apparatus which at the proper moment opens a valve in the leg of the T to admit a full flow and pressure of water direct from the supply side of the alarm valve. The T valve is held closed by a spring while the apparatus is set, at which time there is atmospheric pressure within the T; but upon the opening of a sprinkler head, with consequent flow of water and opening of the alarm valve in the main riser the T becomes filled with water under pressure. The top of the T contains a diaphragm by means of which this pressure overcomes the spring and permits the T valve to open. Being once open it is thereafter maintained open by the di-

rect pressure of water from the main system; and the flow therefrom is utilized to maintain the alarm-giving apparatus in continuous operation.

The invention is represented in the accompanying drawing in connection with a well-known system for actuating an alarm, but as it is readily adaptable to various other systems having similar functions, the embodiment shown is merely illustrative. It is intended that the patent shall cover by suitable expression in the appended claims whatever features of patentable novelty exist in the invention disclosed.

In the drawing herewith the single figure shows an alarm actuating apparatus embodying the invention.

Referring to the drawing, there is shown a part of the water supply to a sprinkler containing an alarm valve 10 through which the main supply of water under pressure passes from the entrance 12 out through the discharge portion 14 into the distributing pipes of the system. The alarm valve 10 may be of any suitable type, and is here shown having a clapper which closes the main opening of the valve as well as an annular groove 18, constituting a differential or intermediate chamber, formed in the seat 20 thereof. A passage 22 from this intermediate chamber 18 leads through a pipe 24, in which is a T valve coupling 26, to a drip or retarding chamber 30. When set, and waiting for the apparatus to be called into action, this drip chamber has a drain 32 open to atmosphere; but this may be closed by a lid 34 according to well known arrangements, or by other suitable means which remain so as to permit the free discharge of any small amount of water entering the drip chamber as by leakage through the valve 10, but which are so restricted as to prevent escape of the greater flow which occurs upon the raising of the alarm valve 10 from its seat, consequent upon the opening of a sprinkler. In the apparatus illustrated the accumulation of water causes the spring supported bottom 38 of the drip chamber to be depressed. This brings down the lid 34 and seals the drain 32; and a continuance of the flow builds up a column of water which rises through pipe 40 to start the alarm actuating apparatus 42. It would be supposed that this water would keep the alarm apparatus in continuous action. In practice, however, the alarm is sometimes intermittent,

To correct this the present invention provides means.

In the embodiment here illustrated a **T** coupling 26 of special design is inserted in the passage 22 with the head of the **T** forming a part of the passage, and with the leg of the **T** providing for the junction therewith of a pipe 44 from any constant supply of water under pressure which in this instance may conveniently be the water supply of the main system. The **T** coupling comprises a hollow body portion on opposite sides of which its entrance and exit pipes 24 of the passage 22 are connected, and to the bottom of which the pressure pipe 44 is joined. This bottom opening in the coupling chamber is normally closed by a conical faced valve 48 whose stem 50 extends upwardly through the chamber into engagement with a compression spring 52 which tends to keep the valve on its seat and is strong enough to do so against the mere pressure of supply in pipe 44. The stem also carries a diaphragm 56 which is clamped thereto between the flange disk 58 of the stem and a backing plate 60 held in place by a nut 62. The diaphragm is tightly clamped at its perimeter between the body and cover of the coupling. Thus the diaphragm forms the top of the chamber and constitutes a movable wall in the passage 22 from the alarm valve 10 to the retarding chamber 30. The cover, above the diaphragm, has a central recess for the spring 52, and also has a shallow annular recess 64 which provides a seat for the backing plate when the valve 48 is raised and is under heavy upward pressure from the water admitted by the opening of valve 48.

In operation, the valve 48 ordinarily remains closed. Leakage and drip flow of water proceeds through the coupling chamber 26 and drip chamber 30 at atmospheric pressure; and the only force tending to open the valve 48 is the high water pressure in pipe 44. But when the opening of alarm valve 10 increases the flow so that a column of water rises in the drip chamber, upward pressure begins to be exerted on the diaphragm 56. The latter is of such large diameter that a relatively low head, caused by the column in the drip chamber 30, will be sufficient when pressing upward on the diaphragm in conjunction with the pressure exerted by the water in the pipe 44 on the face of the valve 48 to lift the latter, overcoming the pressure exerted by the spring 52 on the upper end of the valve stem. The upward pressure on the diaphragm is immediately increased by this accession. Being constant and high this pressure will hold the diaphragm up and keep the valve 48 open even though the alarm valve 10 becomes closed. The valve in the coupling being thus held open the pressure of water in the supply

pipe is constantly transmitted through the system to the alarm actuating apparatus, or to other apparatus, thereby insuring its steady and continuous operation.

If other devices are to be operated such as a water motor or the like, connections may be made thereto or to the alarm by the pipe 66 connected to the system between the valve **T** coupling and the drip chamber, or by the pipe 68 above the latter, from either of which, once the valve has opened, the supply of water will be constant at the same pressure as exists in the main supply system. Although the valve coupling has been described as a **T**, constituting a part of the passage 22 and providing for the introduction of a branch thereinto, and is shown with the valve 48 working vertically, it is obvious that it could be attached otherwise to the system and would operate any side up.

The invention thus described has numerous advantages in addition to those already mentioned. It can be handled and installed as a separate piece of apparatus additional to alarm valve installations already existing, by merely setting it in the line of piping which leads from the alarm valve to the drip chamber and accumulator, without changing any of the existing parts except the pipe connection. Or without disturbing the pipe connection it can be added direct to the accumulator by tapping in through the hole for a connection through a single inlet, which in that case serves the purpose of the two inlets illustrated in the drawing for the pipe 24, the other inlet provided therefor in the chamber being plugged and the bottom inlet connected to pressure supply as described. It can for these reasons be added to any type of drip chamber. By reason of the arrangement of the valve in the leg of the **T** as a puppet valve with the high pressure supply against one face of it the valve is sure to open when the proper conditions arise, because of the direct and powerful effect of the high pressure supply which may be considered to be ordinarily in the vicinity of sixty pounds per square inch. Because of the straight valve stem and rectilinear movement of the valve stem and diaphragm there is no friction. And when closed it will be closed tight because of the direct nature of the pressure supplied by the spring, without angles or slip joints. If desired this apparatus may be used for testing the alarm. To that end the casing cover is represented as being perforated centrally, with the stem of the valve projecting so as to be reached to be pulled up by hand. A removable cap 70 ordinarily covers and protects the valve stem from unauthorized interference. Although the pressure supply to which the device is connected will ordinarily and most conveniently be the main supply of water for sprinklers, in advance

of the alarm valve, it is obvious that the connection may, if desired, be made of any source of supply.

I claim as my invention:

- 5 1. An attachment for an automatic sprinkler system having a valve, said valve being in the water supply part of the system, opened by flow of water therethrough and subject to closure by surge therein, comprising the combination, with a passage having an inlet controlled by said valve, having a restricted discharge, and communicating with apparatus to be operated by accumulation of water from inflow exceeding capacity of discharge, of a second inlet to said passage connected with the system on the supply side of said valve and continuously open to pressure thereof; a valve for the second inlet arranged with pressure of the supply fluid tending to open it; yielding means for maintaining said valve of the second inlet closed; and a movable wall for the passage, engaging the stem of the second valve and having large area relative to the area of that valve, whereby the accumulation of a small head of water counterbalances said yieldable closing means enough to permit the opening of said second inlet valve, and the resulting increase of pressure maintains the second inlet valve open. 70
- 10 2. An attachment for an automatic sprinkler system having a main supply pipe with subsidiary outlet-passage into which the flow is subject to delay by surge, which has restricted outflow, and wherein a large inflow will produce an accumulation of water to actuate auxiliary apparatus, comprising the combination of a separate inlet from high pressure supply to said passage, a valve therefor, and a chamber within the passage, at said inlet, having means sensitive to pressure from accumulated water in said passage and a connection therefrom for opening said valve; whereby the enhanced flow and pressure, thus separately entering from the high pressure supply, maintain the valve open and so maintain the accumulation of water for continuous actuation of said apparatus. 75
- 15 3. In an automatic sprinkler system, the combination of an auxiliary chamber having two inlets from the main sprinkler supply pipe, and having connection to an accumulator, one of said inlets being controlled by means operated by flow in the main pipe, means for maintaining the other of the inlets ordinarily closed in the absence of said flow, and means whereby it is opened upon the accumulation of a small head of water in the accumulator. 80
- 20 4. An attachment for an automatic sprinkler system comprising a casing containing a chamber adapted to constitute part of a passage between an alarm valve in the main
- 25 supply pipe and an accumulator; said chamber having inlet and outlet for the passage, and having in addition a side inlet, and there being, in combination therewith, means within the casing adapted to close said side inlet against high pressure water supply external to the chamber, and means exposed within the chamber to open said side inlet when pressed by a small internal head of water from the accumulator. 85
- 30 5. An attachment for an automatic sprinkler system comprising a casing containing a chamber adapted for connection to an accumulator of water; said chamber having an additional inlet, and there being, in combination therewith, means within the casing adapted to close said additional inlet against high pressure water supply external to the chamber, and means exposed within the chamber to open said additional inlet when pressed by a small internal head of water from the accumulator. 90
- 35 6. An attachment for an automatic sprinkler system having a main supply pipe with a subsidiary outlet-passage in which the flow is subject to delay by surge, comprising the combination of a chamber in said passage having a restricted discharge wherein an inflow exceeding the discharge will produce an accumulation of water to actuate auxiliary apparatus; a second chamber in said passage having a separate inlet from a high pressure water supply, a valve therefor normally closed but adapted to be opened by pressure from the accumulation in the first said chamber whereby water thus admitted thereafter maintains the accumulation for continuous actuation of the auxiliary apparatus. 95
- 40 7. An attachment for an automatic sprinkler system having a main supply pipe with subsidiary outlet-passage into which the flow is subject to delay by surge, which has restricted outflow, and wherein a large inflow will produce an accumulation of water to actuate auxiliary apparatus, in combination with a casing with which said passage communicates, having a separate inlet from high pressure supply, and comprising a chamber having a diaphragm adapted to be moved outward by pressure from accumulated water in the passage, a valve normally closing said separate inlet having a stem attached to said diaphragm, a spring acting on said stem tending to keep the valve closed but yielding to the pressure of the accumulated water on the diaphragm to open said valve, whereby upon yielding of the diaphragm water from the high pressure supply pipe maintains the diaphragm outward. 100
- 45 8. An attachment for an automatic sprinkler system having a main supply pipe with subsidiary outlet-passage into which the flow is subject to delay by surge, which has restricted outflow, and wherein a large inflow 105

will produce an accumulation of water to actuate auxiliary apparatus, in combination with a casing with which said passage communicates, having a separate inlet from high pressure supply, and comprising a chamber having a diaphragm adapted to be moved outward by pressure from accumulated water in the passage, a valve normally closing said separate inlet having a stem attached to said diaphragm, extending outside of said casing and adapted to be engaged manually from without, a spring acting on said stem tending to keep the valve closed but yielding to said manual force, whereby on application 15 of said force the valve opens and water from the high pressure supply maintains it open, causing said accumulation of water to actuate the auxiliary apparatus.

9. An attachment for an automatic sprinkler system having a main supply pipe with subsidiary out-let passage into which the flow is subject to delay by surge, which has restricted outflow, and wherein a large inflow will produce an accumulation of water to 25 actuate auxiliary apparatus, in combination with a casing with which said passage communicates, having a separate inlet from high pressure supply, and comprising a chamber having a diaphragm adapted to be moved 30 outward by pressure from accumulated water in the passage, a valve normally closing said

separate inlet having a stem attached to said diaphragm, a spring acting on said stem tending to keep the valve closed but yielding to the pressure of the accumulated water 35 on the diaphragm to open said valve, whereby upon yielding of the diaphragm water from the high pressure supply pipe maintains the diaphragm outward, and means for drawing the diaphragm outward, thereby to open said separate inlet from without 40 the system.

10. An attachment for an automatic sprinkler system comprising a casing containing a chamber adapted for connection to an accumulator of water; said chamber having an additional inlet, and there being, in combination therewith, means within the casing adapted to close said additional inlet against high pressure water supply external 50 to the chamber, and means exposed within the chamber to open said additional inlet when pressed by a small internal head of water from the accumulator; there being means for external draft upon said internal closing means, whereby the additional inlet 55 may be opened manually.

Signed at Providence, county of Providence and State of Rhode Island, this 15th day of February, 1921.

JONATHAN C. MELOON.
